UNITED STATES PATENT OFFICE.

GEORGE F. ROSE, OF NEW YORK, N. Y.

TYPE-WRITER.

1,138,317.

Specification of Letters Patent. Patented May 4, 1915.

Application filed June 15, 1909. Serial No. 502,207.

To all whom it may concern:

Be it known that I, GEORGE F. ROSE, a citizen of the United States, residing in the city of New York, borough of Manhattan, 5 county and State of New York, have invented certain new and useful Type-Writers, of which the following is a specification.

This invention is a typewriter, and it pertains more particularly to the key action of 10 a front strike machine.

The objects in view are, first, to accelerate the upward movement of the type-bar, whereby the stroke is quickened, the force of the impact is increased, the effort on the part of 15 the operator is lessened, and the rebound of the type bar from the platen is utilized, in a measure, to return the components of the key action to normal positions; second, to facilitate the assemblage of the parts and 20 to minimize the adjustment required in securing alinement of the type impressions, and, thirdly, to secure economy in the manufacture of the parts.

In one embodiment of my new key action, 25 the type bar is provided with a heel and with a plurality of notches. With said type bar co-operates a movable member formed with a notch or opening which produces a prong and a hook, said prong being so related to the heel that it will tend to swing 30 the type bar upwardly, whereas the hook precludes separation of the movable member from the heel of the type bar and tends, also, to return said type bar back to normal position following the rebound from the platen. Said movable member is, preferably, pivoted 35 separately from the pivot of the type bar, and said pivoted member is connected by a link to the key lever and it engages directly 40 with a part of the pivoted type bar, said parts acting to compound the leverage, whereby the stroke of the type bar relatively to the range of movement of the key lever is greatly magnified, and the type bar as it 45 approaches a platen is accelerated, this last mentioned function being secured by the compound leverage referred to and, also, by reason of contacting cam surfaces on the prong of the pivoted member and the heel 50 of the pivoted type bar.

The invention embodies, also, a bracket adapted to be fastened in position on the segment by a screw and to have its position determined accurately at the time it is assembled by centering devices. The securing 55 screws and the centering pins for a plural-

ity of brackets are each arranged on the segment in concentric circles whose common center is the printing point, the securing pin and centering pin for any one bracket being 60 located in the same radius of such circles. It is preferred to employ a bracket which supports the pivoted type bar and the pivoted member or lever; and, furthermore, to construct said bracket in an integral piece, one 65 form of the bracket being stamped from sheet metal and bent or pressed into the required shape and size.

Another part of the invention is a support for the key lever, said support being 70 provided with a slot whereby it may be placed in position on a rail of the machine frame so as to be held in said position by frictional engagement therewith. With said support co-operates a centering stud adapted 75 to enter the support and determine accurately its position on the rail, said stud operating, also, to steady the support on the rail and to preclude accidental displacement thereon, and separation therefrom.

Other parts of the invention will be set forth in the detailed description hereinafter given.

In the accompanying drawings I have illustrated one practical embodiment of the 85 invention, but the construction shown therein is to be understood as illustrative, only, and not as defining the limits of the invention.

Figure 1 is a side elevation illustrating my 90 key action, with a part of the machine frame and the segment in cross section. Fig. 2 is a detached view in side elevation of the type bar. Fig. 3 is a detached view in side elevation of the actuating lever. Fig. 4 is a 95 detail perspective view of the bracket adapted to carry the pivots of the type bar and its actuating lever, respectively. Fig. 5 is a plan view of the blank from which the supporting bar of Fig. 4 is adapted to be produced. Fig. 6 is a detail plan view showing a part of the machine frame and the means for supporting the key lever thereon. Fig. 7 is a detail perspective view of the parts shown in Fig. 6, the key lever being omitted. 100 Fig. 8 is a diagrammatic view, with the segment in rear elevation, illustrating the arrangement of the securing screws and the centering pins for a series of brackets adapted to support a like number of type bars and 105 the actuating levers therefor.

The supporting frame for the key action

may be of any suitable or preferred construction, but as this frame is an immaterial part of the invention, I have thought it necessary only to show the segment at A and 5 a supporting rail at B. The segment is similar to the general form of segments employed in front strike machines, and to said segment is attached a supporting bracket for each type of the series employed in the 10 construction of the key actions. For the sake of clearness, I have shown only one key action in the drawings, but it will be understood that duplicates of these key actions are employed for the several type characters, 15 numerals, and other printing characters.

The bracket which I prefer to use is shown in detail in Figs. 4 and 5 of the drawings, and is represented, also, in Fig. 1 as supporting the type bar and its actuating lever. Said bracket is indicated in its entirety by the reference character C, and it is composed, preferably, of pressed steel, said bracket being bent from a single piece blank, C', of the form shown in Fig. 5. Said 20 blank consists of a stem, c, wings, c', ears, c'', and a lug, c''. The wings and ears are perforated at c', c'', respectively.

The blank is folded or doubled upon itself along the middle line of stem, c, thus bringing the wings, c', into parallel relation to each other, and likewise bringing the ears, c'', into parallel relation to each other. The lug, c'', extends upwardly from one wing of the bracket, as shown in Figs. 1, 4 and 5, 25 and this lug is adapted, in certain of the brackets, to serve as a guide for the type bar in the swinging movement thereof. When the brackets are placed in inclined positions, as toward the ends of the row of 30 type bars, the lugs of said inclined brackets serve as side supports for the type bars, but to reduce the frictional engagement between the lug and the swinging type bar, I prefer to skeletonize each lug, as shown, to minimize the frictional contact of the type bar 35 with the metal composing the lug. Furthermore, each bracket, or its lug, c'', may be, or is, provided with a stop for limiting the upward swinging movement of the type bar, 40 said stop being shown in Figs. 1 and 5 in the form of a pin, d, the latter being in the path of an edge of the type bar.

It is preferred to fasten the type bar bracket to the segment by a single screw, 45 D, and for this purpose stem, c, of the bracket is provided with a threaded aperture, d'. In assembling the bracket on the segment, the closed side of the doubled bracket is placed against the inner face of 50 the segment so that the threaded aperture, d', of said bracket will register or align with a smooth walled opening, d'', provided in the segment, after which screw, D, is inserted in said opening, d'', and by rotating 55 the screw its threads are caused to engage

with the threads of aperture, d', thereby fastening the bracket, C, firmly against the segment.

For the purpose of assembling the brackets quickly and accurately with reference to the segment, I provide the segment with centering holes, e, and the bracket with similar centering holes, e', whereby the bracket may be placed in position for the holes, e, e', to register, and said bracket may thereby be retained in position by inserting a centering pin, E, into said registering holes.

By reference to Fig. 8 it will be noted that the centering pins E for the series of brackets are arranged on the segment in an arc of a circle whose center is the printing point for the type bars; and that the screws D employed to fasten the brackets fixedly in position are also in an arc of a circle whose center is the printing point, the arc for the screws D being concentric to the arc for the centering pins E. Accordingly, the holes e, d'' in the segment for the reception of the center pins E and screws D respectively are each arranged on the segment in concentric arcs of circles whose common center is the printing point; and, further, the screw D and the pin E for each bracket are located in the same radius of such circles.

When the wings, c', and the lugs, c'', are 45 folded into parallel relation in the manner heretofore described, the holes, c', are brought into register, and likewise the holes, c'', are caused to register, whereby pivot pins, f, g, may be inserted in the holes for 50 the purpose of pivotally connecting type bar, F, and actuating-lever, G, to bracket, C.

By reference to Fig. 1 of the drawings it will be noted that centering pin, E, is located directly in line with fulcrum pin, f, 55 of type bar, F, so that the type bar can be rotated slightly on it, thus facilitating the operation of spacing the type bars in the basket of the machine.

The type bar is composed of a single piece 60 of metal, preferably a single piece stamping of pressed steel. As is usual, the type bar is provided with a type head, f', and at the other end said type bar is peculiarly constructed, as shown in Figs. 1 and 2, so as 65 to produce a heel, f''. The heel is provided with a cam shaped edge, h, on one side, and with a curved edge, h', on the opposite side. The cam shaped edge, h, extends upwardly to a rounded notch, h'', said heel of the type 70 bar having a recess, h', with which communicates notch, h''. The curved edge, h', of heel, f'', opens into a notch, h'.

The actuating lever, G, is composed of a one piece stamping of pressed steel, and said 75 lever is disposed in an upright position, its lower end being pivoted by pin, g, between ears, c'', of bracket, C. At its upper end said lever, G, is provided with a finger, g', and a hook, g'', said finger and hook being spaced 80

so as to produce an opening which is adapted for the reception of heel, f^2 , of the pivoted type bar, as shown in Fig. 1. The inner edge of finger, g' , is shaped to produce a cam surface which is adapted to co-act with the cam surface h , of heel, f^2 , on the type bar, whereas the hook, g^2 , is shaped to conform practically to the curved edge, h' , of said heel, f^2 , for the purpose of keeping the hook in engagement with the curved edge, h' , of the type bar heel during the swinging movement thereof, whereby the hook operates to retain actuating lever, G, in engagement with the type bar when the latter is operated by swinging it upwardly and rearwardly, or downwardly and forwardly.

H designates a key lever composed, preferably, of a single piece stamping of pressed steel, although the particular material of the lever is not essential. Said lever is provided at one end with an arm, i , extending at an angle from the body portion of the lever, said arm forming practically a bell crank lever. The key lever is operatively connected with actuating lever, G, by an intermediate link, I. This link is practically a spring, for the reason that it is composed of wire or ribbon steel, bent or looped upon itself one or more times so as to form a coil or coils, i' , intermediate the ends of said link. One end portion of the link is pivotally connected, as at i^2 , to the upstanding free end of arm, i , of key lever, H, whereas the other end of the link is connected at i^3 to the stem of actuating lever, G, said connection, i^2 , being at a point intermediate pivot pin, g , and the operating end of said lever, G, see Fig. 1.

The key lever is fulcrumed at its knee by a pin, j , which is supported in a key lever bracket, J, shown in Figs. 1, 6 and 7 of the drawings. Said key lever bracket is preferably a single piece stamping of pressed steel, and it consists of a plate which is doubled upon itself, as shown in said Figs. 6 and 7. The members of the folded plate are provided with openings, j' , to receive pivot pin, j , and said bracket, J, is provided with notches, k , in the folded members of the plate composing the bracket. Said notches are positioned close to the apertures, j' , and they extend through the lower edge of bracket, J, whereby the bracket may be slipped into position on the supporting rail, B. For the purpose of determining the position of each key lever bracket, J, said rail, B, is provided with an upstanding center pin, h' , the latter being adapted to enter the space of the bracket at the folded edge thereof when said bracket is fitted into frictional engagement with rail, B, by pressing the notched part, k , of the bracket into position over said rail. It is preferred to make the center pin, h' , of angular form in cross section, the shape being preferably square,

whereby the center pin co-operates with the notched part of the bracket in determining the position of said bracket and in retaining the bracket against displacement on the rail.

The operation of the key action will be readily understood from the foregoing description taken in connection with the drawings, but it is desired to call attention to the fact that by pivoting the key lever independently of the type bar, and by employing the pivoted actuating lever intermediate the pivot of the type bar and the fulcrum of the lever, the desired quick action on the type bar, coupled with a minimum depression of the key lever, is secured. Furthermore, the co-operating cam surfaces of finger, g' , on the actuating lever, G, and on the edge, h , of the type bar heel secures the important function of accelerating the upward and rearward stroke of the type bar, for the reason that the forward movement of the lever, G, causes the cam face of finger, g' , to so act on the cam shaped edge, h , of heel, f^2 , that the quickest part of the movement of type bar, F, is the last part of the stroke of said type bar as it approaches the platen. The effective stroke of type bar, F, is arrested by stop, d , so as to preclude the heel, f^2 , from passing out of engagement with prong, g^2 , of actuating member, G. The rebound of type bar after it strikes the platen and the particular relation of the parts comprised in the action, returns the type bar quickly to its normal horizontal position. The employment of spring link, I, intermediate the actuating lever and the key lever tends to reduce the shock to the finger of the operator during rapid operation of the machine, said spring link yielding at its bent or looped portion when the key lever is depressed, particularly when it is struck with considerable force, but at the same time said link imparts the proper operation to the actuating lever to throw the type upwardly against the platen.

The action is rapid and efficient in operation, and it is not liable to get out of order. The parts may be assembled quickly and accurately, and by reason of their construction, the key action is economical to manufacture. The several parts are assembled accurately and quickly, which is an important construction in the economical manufacture of typewriters.

Having thus fully described the invention, what I claim as new, and desire to secure by Letters Patent is:

1. In a typewriter, the combination with a segment, of a bracket connected by a centering pin and a fastening screw to the segment, said centering pin and fastening screw being located in concentric arcs of circles whose common center is the printing point and the pin and screw for said bracket being positioned in the same radius of such

- circles, a type bar, an actuating member therefor, said type bar and the actuating member being both carried by the same bracket so as to be shiftable therewith relative to the centering pin, and a key lever supported independently of the bracket, said key lever having a yielding connection with said actuating member.
2. In a typewriter, the combination with a segment, of a bracket, a centering pin therefor, fastening means for fixedly securing the bracket in position, said centering pin and fastening means being located in concentric arcs of circles whose common center is the printing point and positioned, also, in the same radius of such circles, a type bar pivoted to the bracket, an actuating member for said type bar also pivoted to the bracket, said type bar and its actuating member being shiftable with the bracket relative to the centering pin, and a key lever supported independently of said bracket, said key lever being operatively connected with said actuating member.
- 25 3. In a typewriter, the combination with a segment, of a series of brackets each pivoted to the segment, said pivot of the brackets being positioned in a circle whose center is the printing point, type bars, actuating members therefor, said type bar and the actuating member for each bracket being both supported in the same bracket and shiftable therewith relative to the pivotal support for said bracket, and fastening means separate from the pivot for fixedly securing each bracket in position on the segment.
4. In a typewriter, the combination with a segment, of a series of brackets each connected thereto by a centering pin, the centering pin of each bracket being positioned in the arc of a circle whose center is the printing point, a type bar pivoted to the bracket, a type bar actuating member pivoted to the bracket independently of the pivot of the type bar, fastening means separate from the centering pins for fixedly securing the bracket in position on the segment, said type bar and the actuating member being shiftable with the bracket relative to the center pin, a key lever having an operative connection with said actuating member, and supporting means for said key lever, said supporting means being independent of the bracket and positioned forwardly thereof.
5. In a typewriter, the combination with a segment, of a bracket connected to said segment by a centering pin, fastening means separate from the centering pin for fixedly securing the bracket to the segment, a type bar pivoted to the bracket, the centering pin of the bracket being positioned rearwardly of the pivot for the type bar, a type bar actuating member supported on said bracket, a key lever having an operative connection with said actuating member, and supporting means for said key lever, said supporting means being independent of the bracket and positioned forwardly thereof.
6. In a typewriter, the combination with a segment, of a bracket provided near one end with means for supporting a type bar and near its other end with means for supporting an actuating member for said type bar, said bracket being connected by a centering pin to the segment, a type bar pivoted to the supporting means provided therefor on the bracket, the pivot of the type bar being at a right angle to the centering pin, an actuating member pivoted to the supporting means on said bracket, said type bar and the actuating member being shiftable with said bracket, a key lever having an operative connection with said actuating member, and supporting means for said key lever, said supporting means being independent of the bracket and positioned forwardly thereof.
7. In a typewriter, a segment, a bracket, a type bar pivoted to the bracket, a centering pin co-operating with the bracket and the segment, said centering pin being positioned substantially in the horizontal plane of and rearwardly with respect to the type bar pivot, and means separate from the centering pin for fixedly securing the bracket in position.
8. In a typewriter key action, the combination of a single bracket embodying a shank provided at one end with a pair of lugs and at its other end with a separate pair of lugs, a segment, centering means connected to the segment and the shank of said bracket for determining the relation of said bracket to the printing point, securing means separate from the centering means for fixedly attaching the bracket to the segment, a type-bar pivoted in one pair of lugs, and a type-bar actuating member pivoted in the other pair of lugs, said actuating member and the type bar being supported by said single bracket and being shiftable therewith relative to the centering means.
9. In a typewriter key action, the combination of a single bracket provided with separate supporting means for a type-bar and for an actuating member, in combination with a segment, centering means connecting the bracket to the segment for determining the relation of said bracket to the printing point, fastening means separate from the centering means for fixedly securing the bracket to the segment, a type-bar pivoted to one of the supporting means on the bracket, an actuator pivoted to the other supporting means on the bracket, said actuator being connected to the type-bar, and said actuator and type-bar being shiftable with the bracket on the centering means, a key lever having an operative connection with said actuating member, and supporting

means for said key lever, said supporting means being independent of the bracket and positioned forwardly thereof.

16. In a typewriter, a segment, a supporting bracket having means for centering the same in position relative to the segment, a type bar pivoted to the bracket at one end thereof, a type bar actuating member pivoted to the bracket at the other end thereof, 5 said type bar and the actuating member being shiftable with the bracket relative to the segment, a key having an operative connection with said actuating member, and supporting means for said key lever, said supporting means being independent of the bracket and positioned forwardly thereof.

11. In a typewriter, a segment, a supporting bracket having means for centering the same in position relative to the segment, separate means for fixedly securing the bracket in position on the segment, a type bar mounted in the bracket, a type bar actuating member pivoted to the bracket and engaging with the type bar, said type bar and the actuating member being shiftable with the bracket relative to the segment, a key lever having an operative connection with said actuating member, and supporting means for said key lever, said supporting means being independent of the bracket and positioned forwardly thereof.

12. In a typewriter; a segment, a pivoted type bar, a pivoted member co-operating therewith, a bracket having means for supporting the type bar and the pivoted member, said bracket having means for centering it in position relative to the segment, separate means for clamping said bracket fixedly in position on the segment, a key lever having an operative connection with said actuating member, and supporting means for said key lever, said supporting means being independent of the bracket and positioned forwardly thereof.

45 13. In a typewriter, a frame, a notched bracket fitted to said frame and held in posi-

tion by frictional engagement therewith, a key lever mounted in said bracket, and a type bar operated by said key lever.

14. In a typewriter, a frame, a center stud 50 on said frame, a bracket engaging said stud and supported on the frame, a key lever mounted on the bracket, and a type bar operated by said key lever.

15. In a typewriter key action, the combination of a segment, a type-bar bracket attached thereto, a type-bar pivoted to said bracket, and a type-bar supporting ear in fixed relation to the bracket and extending outwardly beyond the plane of the type-bar pivot, said ear being positioned at one side only of the type-bar and being free from contact therewith in the normal position of said type-bar, whereby the type-bar when moved into printing position is adapted to 60 have contact on one face only with the opposing face of the ear.

16. In a typewriter key action, the combination of a segment, a type-bar bracket attached thereto, said bracket being provided with a pair of lugs and with a single supporting ear extending outwardly from one of said lugs and positioned in the same plane therewith, a type-bar having one end fitted between said lugs of the pair on the 75 bracket, and a pivot connecting the type-bar and the pair of lugs, said supporting ear being positioned at one side only of the type-bar and being free from contact therewith in the normal position of the type-bar, 80 whereby the type-bar when moved into printing position is adapted to have contact on one face only with the opposing face of the lug.

In testimony whereof I have signed my 85 name to this specification in the presence of two subscribing witnesses.
